CLAIM

The ornamental design for a dental instrument with light display, as shown and described.

DESCRIPTION

FIG. 1 is a perspective view of a dental instrument with light display showing the claimed design;

FIG. 2 is a front perspective view thereof;

FIG. 3 is a rear perspective view thereof;

FIG. 4 is a left side view thereof;

FIG. 5 is a right side view thereof;

FIG. 6 is a top perspective view thereof;

FIG. 7 is a bottom perspective view thereof; and,

FIG. 8 is an enlarged front view of the portion shown in dot-dot-dash lines in FIG. 2.

The broken lines in the figures show portions of the dental instrument with light display that form no part of the claimed design.

The dot-dot-dash broken lines in FIG. 2 indicate from where the enlarged view in FIG. 8 is taken and form no part of the claimed design.

FIGS. 1-8 are shaded to show an illuminated appearance.

The gray shaded areas of FIGS. 1-8 represent areas emitting (Continued)

or illuminated by light, and the white areas that form part of the claimed design in FIGS. 1-8 represent areas not emitting light.
